Attorney

two phase type, an adjustable phase shifter 31 for properly adjusting the phase of that input.

Referring now to Fig. 2 there is shown a curve 24 representing the radio frequency output signal across inductance 12, and similarly across coil 19, as a function of the total capacity in the tuned circuit. If it is assumed that the total value of the capacity of the tuned circuit is such that the circuit is operating at point 25 of curve 24 with respect to the frequency of the incoming signal, it is obvious that the capacity of the tuned circuit must be increased to bring the amplifier to its optimum operating point, namely point 26 of curve 24. On the other hand, operation at point 27 would require a decrease in total capacity.

Now, assuming that the circuit is operating at point 25, variation in capacity 15 by motor 16 would vary the total capacity of the tuned circuit in accordance with curve 28a, resulting in a variation in the output of the tuned circuit in accordance with wave 29a. Similarly, operation at point 27 would cause the variations in the total capacity, represented by wave form 28b, to produce an output variation corresponding to wave form 29b. It can be readily seen that the outputs 29a, 29b, are of equal amplitude and frequency, but are 180 degrees out of phase. On the other hand if the tuned circuit was operating at the optimum point with respect to the frequency of the incoming radio frequency signal, namely point 26, variations in capacitance 15 in accordance with curve 28c, which is equal to curves 28a and 28b, would produce an output variation corresponding to curve 29c which is of double the frequency of curves 29a and 29b.

By arranging detector 21 and amplifier 22 to be responsive only to frequency variations corresponding to curves 29a and 29b, and by utilizing any well-known phase discriminator as the detector, it can be readily seen that the signal supplied to motor 23 will be proper to tune the resonant or tank circuit to its optimum operating point and maintain the circuit at this point.

It is to be understood that the particular arrangement of the detector and motor control forms no part of this invention and that any well-known arrangement may be utilized. For example, the control circuit may be of the type illustrated in U. S. Patent No. 2,380,947, dated August 7, 1945, to Murray G. Crosby. In this arrangement, the control voltage would be derived from the output across coil 19. By placing additional tank circuit condensers on the same shaft as capacitor 13, the system of the present invention may be applied to multi-stage amplifiers. Any other suitable control arrangement may be utilized without departing from the spirit and scope of the present invention as defined in the appended claims.

The invention described herein may be manufactured and used by or for the Government of the United States of America for governmental purposes without the payment of any royalties thereon or therefor.

What is claimed is:

1. In a radio frequency amplifying network having a resonant output circuit including a variable condenser, an automatic tuning device for tuning said circuit to its optimum operating point with respect to the frequency of the signal to be amplified, said device comprising a second variable condenser connected across the circuit condenser, means for periodically varying the

capacity of said second condenser to thereby vary the output of the resonant circuit, motive means for varying the capacity of said circuit condenser, and means responsive to the phase of the output of said circuit for controlling the operation of said motive means.

2. An automatic tuning device for a resonant circuit having a variable condenser, said device comprising a source of periodically varying energy coupled to the input of said circuit, a second variable condenser connected across the resonant circuit, motive means for periodically varying the capacity of said second condenser to thereby vary the output of said circuit, motive means for varying the capacity of the variable condenser of said circuit, and means responsive to the time displacement of the output of said circuit for controlling the operation of the last-mentioned motive means.

3. A device according to claim 2, wherein said second condenser is of relatively small capacity with respect to said circuit condenser.

4. An automatic tuning device for maintaining a resonant circuit at its optimum operating point with respect to the frequency of a periodically variable signal supplied thereto, said device comprising a variable condenser connected across the circuit, means for periodically varying the capacity of said condenser to thereby vary the output of said circuit, means for varying one of the elements of said circuit, and means responsive to the phase variations in the output of said circuit due to the variations in said condenser for controlling the operation of the last-named varying means.

5. In combination with a parallel resonant circuit, an automatic tuning device for maintaining said circuit at its optimum operating point with respect to the frequency of a periodically varying signal applied to the input thereof, said device comprising a variable reactance connected across the circuit, means for periodically varying the reactance to thereby vary the output of said circuit, means for varying one of the elements of said circuit, and means responsive to the time displacement variations in the output of said circuit due to variations in said reactance for controlling the operation of the last-named varying means.

6. In combination with a source of radio frequency energy and a tunable load circuit coupled to said source, a device for automatically maintaining said circuit at substantial resonance with respect to the frequency of the applied energy, said device comprising means for varying the frequency to which said circuit is tuned, means for tuning said circuit to resonance independently of the first-named means, and electrical means responsive to the phase variations in the output of said circuit due to the variations in the tuning of said circuit by said first-named means for controlling the operation of said tuning means.

7. In combination with a source of electrical energy having a substantially sinusoidal component and a tunable load circuit having its input end coupled to said source, automatic tuning apparatus comprising means coupled to said circuit for varying the frequency to which said circuit is tuned, means for tuning said circuit to resonance independently of the first-named means, and means coupled to the output end of said circuit and responsive to the time displacement of the sinusoidal component output due to the variations in the tuning of said circuit by said

first-named means for controlling the operation of said tuning means.

8. An automatic tuning device for maintaining a tunable load circuit at resonance with respect to the frequency of a sinusoidal component of a signal applied to the input of said circuit, said device comprising means for periodically varying the frequency to which said circuit is tuned, means for independently tuning said circuit to resonance, and means coupled to the output end of said circuit and responsive to the time displacement of the sinusoidal component output due to the variations in the tuning of said

circuit by the first-named means for controlling the operation of said tuning means.
